Primary Examiner — Steven J Czyz(74) *Attorney, Agent, or Firm* — Egbert Law Offices, PLLC(57) **CLAIM**

The ornamental design for a shackle safety device, as shown and described.

DESCRIPTION

FIG. 1 is an upper perspective view of a shackle safety device showing my new design.

FIG. 2 is a lower perspective view thereof;

FIG. 3 is a front view thereof;

FIG. 4 is a rear view thereof;

FIG. 5 is a side view thereof;

FIG. 6 is an opposite side view thereof;

FIG. 7 is a top plan view thereof;

FIG. 8 is a bottom plan view thereof; and,

FIG. 9 is a perspective view of the shackle safety device shown in use for ease of disclosure.

The broken lines depict environment that forms no part of the claimed design.

1 Claim, 3 Drawing Sheets(56)
